UNITED STATES PATENT OFFICE.

GEORGE L. BARRETT, OF SPRINGFIELD, OHIO.

CUT-OUT FOR AN ELECTRIC SIGNAL.

1,171,494.

Specification of Letters Patent. Patented Feb. 15, 1916.

Application filed September 6, 1913. Serial No. 788,427.

To all whom it may concern:

Be it known that I, GEORGE L. BARRETT, a citizen of the United States, residing at Springfield, in the county of Clark and

5 State of Ohio, have invented certain new and useful Improvements in Cut-Out for an Electric Signal, of which the following is a specification, reference being had therein to the accompanying drawing.

10 This invention relates to a cut-out for an electric signal, such as a buzzer or bell, and the object of the invention is to provide such a signal having embodied within itself a cut-out whereby the circuit can be opened 15 and closed at will; and further, to provide such a device which will be very simple in its construction and operation and will add little to the cost of the signal.

In the accompanying drawings, Figure 1 20 is a front elevation of a buzzer embodying my invention showing the casing removed; Fig. 2 is a rear elevation of the same; and Fig. 3 is a vertical, sectional view taken centrally through the same with the casing in 25 place.

In these drawings I have illustrated the invention as applied to a buzzer of a known construction but it will be understood that the device can be applied to signals of different kinds, although it is especially adapted 30 to buzzers and bells. The buzzer here shown comprises a base plate 1 having mounted thereon the usual magnets 2 and vibrator 3.

Mounted on the base 1 are two connectors 35 4 and 5 which extend through the base plate, are insulated therefrom and are connected with the coils of the electro-magnet. The connector 4 is connected directly with the magnet by a conductor 6 arranged on the 40 back of the base plate, while the connector 5 is mounted in electrical contact with the base and is thus connected through the base plate and vibrator 3 with a contact member 5^a, which co-operates with the vibrator and 45 is connected with the electro-magnet 2 by a second conductor, 6^a, on the back of the base plate. The connectors 4 and 5 are preferably connected with the signal circuit on the front of the base and within the casing, as 50 indicated at 7. The connector 4 is, in the present instance, in the form of a binding post and has the wire 8, forming one side of the circuit, connected directly thereto. The connector 5 does not have the wire connected 55 directly thereto, but has that end thereof which is within the casing provided

with a contact surface arranged to be engaged by a movable contact member to which the other side of the circuit is connected.

In the present form of the invention I have provided a lever 9 having mounted thereon a binding post 10 to which is connected the wire 11 forming the other side of the signal circuit. The lever 9, as here 65 shown, comprises two offset portions connected by a transverse portion which extends through an opening in the base plate. The lever 9 as a whole extends across the center of the base plate and is pivotally connected to the base plate near that edge 70 thereof opposite the contact member 5, as indicated at 12. The lever is insulated from the casing, preferably by mounting the metal portion thereof on a strip of insulating material 13 which is pivotally connected at the base. The lower portion of the lever 9 which carries the binding post 10 has a portion extending outward through the casing 75 and forming a handle by means of which 80 the lever may be moved from one position to another. As here shown, the lever, when in a position to open the circuit, is arranged between the conductors 4 and 5 and can be moved to the left, in Fig. 1, so that it will 85 be brought into electrical contact with the contact member 5, thereby closing the circuit through the wires 8 and 11 and the magnet. While the wires of the signal circuit may 90 be led into the casing in any suitable manner I prefer to carry them in from the back through an opening 14. The wire 8 extends directly down to the terminal or binding post 4 but the wire 11 preferably extends upward about the magnets and down the 95 opposite side of the casing and thence to the binding post 10 upon the lever 9, thus forming a loop of wire extending about the casing which will permit of the movement of the lever, to which the wire is connected, 100 without injury to the wire, as might result from a short wire or a wire having a sharp bend therein. I also prefer to provide means for holding the lever firmly in engagement with the contact post or member 105 5. To this end I have applied a spring to the lever and this spring is shown as comprising a substantially U-shaped loop of spring wire 15 mounted on the rear of the base, having its upper ends secured thereto 110 on opposite sides of the lever 9 and its transverse portion extending between the lever

and the base. The U-shaped wire or spring is so connected with the base that if unre-sisted it would extend at a considerable angle to the plane of the base. Conse-
5 quently, when confined beneath the lever 9 it tends to move the rear portion of the lever away from the base and, consequently, tends to move that portion of the lever which lies on the opposite side of the base toward the latter and to hold the same in firm engage-
10 ment with its co-operating contact member. Means are provided for preventing the lever from coming in contact with the casing at a point where it extends through the same, and, to this end, a slotted plate of insulated material 16 is secured within the casing ad-
15 jacent to the opening through which the lever passes and serves to guide the lever and maintain the same out of engagement with the metal casing.

The operation of the device will be readily understood from the foregoing description and it will be apparent that I have provided a very simple cut-out built within the buzzer 25 or bell itself which is of such a character that its operation is certain and there is little liability of it becoming disarranged or broken in ordinary use. Further, the device is of such a character that it can be cheaply 30 constructed and requires little or no change in the construction of the buzzer or other signal.

While I have shown and described one embodiment of my invention it will be un-

derstood that this has been chosen for the 25 purpose of illustration only and that I do not desire to be limited to the details of construction shown and described, for obvious modifications will occur to a person skilled in the art. 40

Having thus fully described my invention, what I claim as new and desire to secure by Letters Patent, is:—

A device of the character described comprising a base having an opening, electrical 45 connectors mounted on said base, an electrical conductor leading to one of said connectors, the other of said connectors comprising a contact member, a lever pivotally mounted on the back of said base on an axis 50 transverse to the plane thereof, extending through the opening in said base to a point near said contact member and having a portion constituting a handle to enable said lever to be moved into and out of engage- 55 ment with said contact member, a second conductor connected to and movable with said lever, and a U-shaped loop of resilient wire having its ends secured to said base on opposite sides of said lever and having its 60 transverse portion extending beneath said lever and exerting outward pressure thereon.

In testimony whereof, I affix my signature in presence of two witnesses.

GEORGE L. BARRETT.
